(57) **CLAIM**

The ornamental design for a handle for a hand-held power operated tool, as shown and described.

DESCRIPTION

FIG. 1 is a top and front perspective view of a handle for a hand-held power operated tool embodying my new design; FIG. 2 is a bottom and rear perspective view thereof; FIG. 3 is a top and rear perspective view thereof; FIG. 4 is a bottom and front perspective view thereof; FIG. 5 is a top plan view thereof; FIG. 6 is a bottom plan view thereof; FIG. 7 is a left side elevation view thereof; FIG. 8 is a right side elevation view thereof; FIG. 9 is a front elevation view thereof; and, FIG. 10 is a rear elevation view thereof.

The broken lines in the drawings illustrate portions of the handle for a hand-held power operated tool that form no part of the claimed design.

1 Claim, 9 Drawing Sheets
